[57] **CLAIM**

The ornamental design for a combined cable channel cutting tool and removable cable guide for firewall lead-in, as shown.

DESCRIPTION

FIG. 1 is a perspective view of one side of the combined cable channel cutting tool and removable cable guide for firewall lead-in showing our design;

FIG. 2 is a perspective view of the other side of the combined cable channel cutting tool and removed cable guide for firewall lead-in;

FIG. 3 is an elevational view of one side of the combined cable channel cutting tool and removable cable guide for firewall lead-in; and

FIG. 4 is an end view of the combined cable channel cutting tool and removable cable guide for firewall lead-in.

FIG. 1
